UNITED STATES PATENT OFFICE.

RICHARDSON H. TAYLOR, OF MEEKER, COLORADO.

DENTAL MANDREL.

Application filed September 17, 1926. Serial No. 136,079.

This invention relates to improvements in dental mandrels.

In the operation of grinding and polishing teeth dentists employ flat disks of abrading material which are secured to suitable mandrels that are rotated at high speed by means of electric motors. These flat disks are, however, unsatisfactory in many respects for they have very little rigidity and therefore flex very readily. This flexing of the disk makes it impossible to exert any great amount of pressure which slows the work and besides this the continual bending soon destroys the disks. It is also evident that a flat grinding surface is not very well adapted for many different locations.

It is the object of this invention to produce a mandrel that is so constructed that a sector shaped grinding disk can be clamped thereto and held in such a way that it will assume the shape of a cone. The grinding surface may be on the inside or on the outside as may be desired. By forming the disk into a cone shape, it will be much more rigid and it will also be adapted to be employed in positions and in relationships where flat disks can not be used.

In order better and more clearly to describe my invention so that its construction and mode of operation can be understood, I shall have reference to the accompanying drawing where the preferred embodiment thereof has been illustrated and in which:

Fig. 1 is a view, with parts broken away, showing one way of using my improved mandrel;

Fig. 2 is a view partly in section, showing the construction of my improved mandrel and the manner in which the disk is secured in place thereto;

Fig. 3 is an end view of the mandrel, looking in the direction of the arrow 3 in Fig. 2; and

Fig. 4 is a view showing the shape of the disk employed.

Numeral 1 represents the shank of my improved mandrel. This mandrel differs from the ordinary mandrel in this, that the head has an opening with conical sides instead of

the flat transverse face of the usual mandrel. As illustrated the head 2 is cone shaped and the outer conical surface terminates in the shoulder 3 and cylindrical surface 4. The end of the head portion has a conical depression terminating in a flat transverse bottom 5. The mandrel has a threaded axial opening 6 extending inwardly from the bottom 5. A screw 7 extends into and has a threaded connection with the opening 6. This screw has a large head 8 whose side is conical and parallel with the side of the opening in the head 2. The grinding disk 10 is clamped between the inner wall of the opening in the head 2 and the side 9 of the head 8 in the manner shown in Fig. 2. The disk 10 may be made in the same manner and shape as the ordinary flat disks now employed but must have a sector removed so as to form a sector-shaped opening 11. When the disk is in place on the mandrel (Fig. 2) the radial sides 12 and 13 of the opening 11 overlap somewhat as shown in Fig. 3 and care should therefore be exercised to overlap the edges in such a way that the edge of the end in contact with the object ground shall follow and not lead (see arrow in Fig. 3).

In Fig. 1 I have shown a tooth and indicated the same by the reference numeral 14; this figure is intended to show one use of this device and illustrates how contact can be made with the tooth down to the gums. There are, of course, many other places where the cone shaped grinding surfaces are superior to the flat ones now ordinarily employed and Fig. 1 is therefore merely shown as an example.

Having now described my invention what I claim as new is:

1. A dental mandrel comprising a shank provided at one end with an integrally formed head of larger diameter, said head having a depression with conical sides, said mandrel having a threaded axial opening extending inwardly from the bottom of the depression and a screw threadedly connected with the side of the opening, said screw having a head whose side is formed by a conical surface which conforms in shape to

the inner surface of the depression and which is adapted to cooperate with the latter to clamp and hold a grinding disk.

2. A dental mandrel having an enlarged head at one end, said head being provided with a conical recess, said mandrel having an opening extending inwardly from the bottom of the recess and a screw threadedly connected with the inner surface of said

opening, said screw having a head with a conical outer surface, said head being adapted to cooperate with the inner surface of the recess in the head for clamping a disk in place.

In testimony whereof I affix my signature.

RICHARDSON H. TAYLOR.
